UNITED STATES PATENT OFFICE

94,721

DESIGN FOR A COMBINATION SALT AND PEPPER SHAKER

Don F. Affolter, St. Louis, Mo.

Application October 13, 1934, Serial No. 53,608

Term of patent 7 years

To all whom it may concern:

Be it known that I, Don F. Affolter, a citizen of the United States, residing at St. Louis, State of Missouri, have invented a new, original, and ornamental Design for a Combination Salt and Pepper Shaker, of which the following is a specification, reference being had to the accompanying drawing, forming a part hereof.

Figure 1 is a side elevational view of the combination salt and pepper shaker, showing my new design; Fig. 2 is an end elevational view thereof; and Fig. 3 is a top plan view thereof.

I claim:

The ornamental design for a combination salt and pepper shaker, as shown.

DON F. AFFOLTER.
